UNITED STATES PATENT OFFICE.

DAVID MINCHENBERG, OF NEW YORK, N. Y.

DESIGN FOR A DRESS.

Application filed October 17, 1928. Serial No. 28,528. Term of patent 14 years.

To all whom it may concern:

Be it known that I, DAVID MINCHENBERG, a citizen of the United States and a resident of the city of New York, borough of Manhattan, in the county of New York and State of New York, have invented the new, original, and ornamental Design for Dresses, of which the following is a specification.

Reference is had to the accompanying drawing forming a part thereof, in which

ing my new design for a dress, the figure being shown by dotted lines:

I claim:

The ornamental design for a dress, as shown and described.

Signed at Manhattan in the county of New York and State of New York this 15th day of October A. D. 1928.

DAVID MINCHENBERG.
